UNITED STATES PATENT OFFICE.

JAMES M. DODGE, OF PHILADELPHIA, PENNSYLVANIA.

COAL-CHUTE.

1,126,418.

Specification of Letters Patent.

Patented Jan. 26, 1915.

Application filed September 25, 1912. Serial No. 722,273.

To all whom it may concern:

Be it known that I, JAMES M. DODGE, a citizen of the United States, residing in Philadelphia, Pennsylvania, have invented 5 certain Improvements in Coal-Chutes, of which the following is a specification.

One object of my invention is to construct a chute for handling coal, and like fragile material, in such a manner that the flow of 10 the coal through the chute can be regulated to prevent any unnecessary breakage of the lumps.

A further object of my invention is to provide a chute of the type having a swing- 15 ing depending section and means for regulating the flow of coal therethrough.

A still further object of the invention is to so construct the depending section that it can be turned up as the pile of coal in- 20 creases in height.

In the accompanying drawings:—Figure 1, is a perspective view illustrating my improved chute in position to receive coal and to deliver it into the hold of a vessel; Fig. 2, 25 is a side view of the chute; Fig. 3, is an end view; Fig. 4, is a plan view of the pivoted chute with the top removed, showing the deflectors; Fig. 5, is a longitudinal sectional view on the line 5—5, Fig. 4; Fig. 6, is a 30 side view in elevation of two sections of the depending portion of the chute; Fig. 7, is a face view of Fig. 6; Fig. 8, is a perspective view of one of the deflectors illustrated in Fig. 7; and Fig. 9, is a diagram view illustrating the travel of the coal through one 35 portion of the chute.

Referring to the drawings, 1, is a structure to which the chute is hung, in the present instance. This structure is located, as illus- 40 trated in Fig. 1, on a wharf, and under the floor 2 is a hopper 3 into which coal is dis- charged from a car.

4 illustrates a vessel or barge having a hatchway 5 into which the chute extends so 45 as to discharge the coal from the hopper into the hold of the vessel.

6 is a chute pivoted at 7, and the chute can be raised or lowered on the pivot by means of the hoisting drum 8 connected by a rope 50 9 to a yoke 10 attached to the outer end of the chute. The chute may be raised or lowered bodily, if necessary, but, in the pres- 55 ent instance, the rear inner end is hung from chains 11. The means for suspending the chute and for raising and lowering it

may be modified without departing from the essential features of the invention.

Pivoted at 12 at the outer end of the chute 6 is a depending chute 13 made of a series of element 14 connected together by 60 pivots 15. This construction enables the depending section to be shortened by turning up the lower element and, as the depending portions are shortened, these elements may be turned up to ride over the portions 6 of 65 the chute, as illustrated in dotted lines, Fig. 2. The elements are raised by a rope 16, which may be operated from the floor 2 or from a platform 17 secured to one side of the chute near the point where the depending portion is hung to the inclined portion 6.

The chute 6 preferably has a cover 18 slotted throughout its length, as shown, and on this cover are rails for carrying the up-turned sections 14 of the depending portion 75 when they are turned over onto the chute, as shown in Figs. 2 and 3. The longitudinal slot allows for the inspection of the interior of the chute, so that an operator standing on the platform 17 can see that the 80 coal is properly fed through the chute.

20 is a series of deflectors pivoted to the side of the main chute at 19. The deflectors alternate first on one side and then on the other, as clearly shown in Fig. 4. Secured 85 to the lower end of the pivot pins 19 for the deflectors 20 are arms 21, which extend under the chute and are attached to a longitudinal operating chain or rope 22, which passes around pulleys 23, 24 and can be 90 moved longitudinally by the hand lever 25 attached to a shaft having a wheel around which passes the chain 22. The shaft may be turned by hand or by power, as desired.

By moving the chain in one direction 95 longitudinally the space between the deflectors is varied so as to increase the deflection of the body of coal passing through the chute. By moving the deflectors in the opposite direction the space for the free flow of coal 100 is increased. Thus the flow of coal is properly regulated and controlled, and disintegration of the lumps is prevented to an appreciable degree. By this construction the operator can regulate the flow of coal 105 through the inclined chute 6, but, in order to prevent the coal dropping from the end of this inclined chute into the hold of a vessel, for instance, I provide deflectors 26 in the depending portion 18. In this case there 110

is a deflector in each element 14 pivoted at one side, and the deflectors project alternately first from one side and then from the other side, so that the coal as it passes through the depending portion flows first over one deflector and then over another deflector, until the coal is finally discharged at the lower end of the depending section, practically without breakage.

- 10 In the rear of each element 14, in the present instance, is a curved slot 27, Fig. 7, through which extends a pin 28 secured to the deflector 26 mounted on a pivot pin 29 adapted to bearings in the side wall of the 15 section. A short chain 31 is attached to the pin 28 and to the operating chain 30, so that upon raising the operating chain the deflectors 26 will be elevated and when the chain 30 is moved in the opposite direction it will 20 permit the deflectors 26 to drop of their own weight, so that the deflectors can be adjusted to any angle desired from the side walls and to such position that one deflector may overlap another, as illustrated 25 in Fig. 7, for the purpose of regulating the flow of coal through the depending portion of the chute.

As above remarked, the depending portion is made of elements 14, pivotally connected to each other so that the lower portion can be turned up, as illustrated in Fig. 1, as the pile of coal in the vessel increases in height.

The rope 16 passes around a portion 32 of 35 the inclined chute and as the elements are drawn up they pass over this round portion and rest upon the rails on the cover or hood 18 of the inclined section, without interfering with the flow of coal through said inclined section.

The chain 30 is attached to a drum 33 at the platform 17 and this is driven from a shaft 34, in the present instance, which is provided with a handle 35.

45 It will be noticed that the operating chain 30 is at the front of the depending portion 13 of the conveyer, so that the turning of the elements 14 as the pile of coal increases in height will not affect the adjustment, 50 through the chain 30, of the main deflectors 26, which are in active use.

While I have shown the particular construction of mechanism for operating these deflectors and a platform at the side of the chute at the point where the depending portion of the chute is connected to the inclined portion, the operating means may extend to other points without departing from the spirit of the invention.

55 I claim:

1. The combination in a chute for coal and analogous material, of a pivoted inclined chute; means for suspending the chute so that it can be arranged at any angle desired; a depending section hung

from the end of the pivoted section and into which the pivoted section discharges, said depending section being made of a series of elements pivotally connected; adjustable, alternately arranged deflectors in the pivoted section of the chute and alternately arranged deflectors in the depending section; means for moving the deflectors of the inclined section of the chute in unison; and means for adjusting the deflectors of the depending section in unison so that the flow of material through the chute may be regulated by the independent adjustments of the two sets of deflectors and the adjustment of the inclined chute. 70 75 80

2. The combination in a chute for coal and analogous material, of a pivoted inclined section and a depending section hung from the outer end of the pivoted section; deflectors alternately projecting from opposite sides of the pivoted inclined section and the depending section; a longitudinally arranged chain for each section connected to the several deflectors so that when one of the chains is moved longitudinally the deflectors, to which it is connected, will be shifted simultaneously. 85 90 95

3. The combination in a chute for coal and analogous material, of a pivoted inclined section; means for adjusting said section; a depending section pivotally connected to the outer end of the pivoted section consisting of a series of elements pivotally connected; a series of alternately arranged deflectors in the pivoted inclined section; a deflector in each pivoted element, the deflectors being alternately arranged; and means on the inclined section for supporting the elements of the depending section when they are raised out of the path 100 105 of the material flowing through the chute. 110

4. The combination of a chute; a depending section, said depending section consisting of a series of elements pivotally connected; means attached to the lowermost element and arranged to raise the chute from the bottom up; a deflector in each of said elements, the deflector of alternate elements projecting from one side of the chute and the other elements projecting from the other side of the chute; and means for adjusting the elements simultaneously to control the flow of material through the chute, the adjusting means being so located as not to be affected by the lifting of the lowermost sections out of the path of the material. 115 120 125

5. The combination of a pivoted chute; a depending section pivotally mounted at the end of the chute; staggered deflectors arranged in the chute and in the depending section; means for operating the deflectors of the chute; and means for operating the deflectors of the depending section; with a platform at the outer end of the chute; the 130

operating means for both the chute and the depending sections terminating at the platform.

6. The combination in a chute for coal and analogous material, of a depending portion consisting of a series of pivotally connected elements; deflectors in said elements; means for simultaneously adjusting the said deflectors in the depending section; and means for lifting the lowermost element out

of the path of the material without interfering with the adjustment of the deflectors in the remaining elements.

In testimony whereof, I have signed my name to this specification, in the presence 15 of two subscribing witnesses.

JAMES M. DODGE.
